UNITED STATES PATENT OFFICE

114,380

DESIGN FOR A VENDING MACHINE

David S. Bond, Brookline, Mass.

Application February 13, 1939, Serial No. 82,938

Term of patent 3½ years

To all whom it may concern:

Be it known that I, David S. Bond, a citizen of the United States, residing at Brookline, and county of Norfolk and State of Massachusetts, have invented a new, original, and ornamental Design for Vending Machines, of which the following is a specification, reference being had to the accompanying drawing, forming a part thereof.

Both sides of the machine are similar.

I claim:

The ornamental design for a vending machine, as shown and described.

DAVID S. BOND.
